Specification for Design.

Patented Apr. 11, 1916.

Application filed April 29, 1915. Serial No. 24,822. Term of patent 14 years.

To all whom it may concern:

Be it known that I, ALFRED C. GILBERT, a citizen of the United States, residing in New Haven, in the county of New Haven and State of Connecticut, have invented a new, original, and ornamental Design for a Toy Girder or Column, of which the following is a specification, when taken in connection with the accompanying drawing.

In the drawing, Figure 1 is a side elevation of a toy girder or column embodying my design; Fig. 2 is an elevation at right angles to Fig. 1; and Fig. 3 is a plan view of the toy girder or column.

What I claim is:—

The ornamental design for a toy girder or column, substantially as shown.

ALFRED C. GILBERT.
